UNITED STATES PATENT OFFICE.

SHELDON A. WILLIAMS, OF DES MOINES, IOWA, ASSIGNOR OF ONE-HALF TO HARRY F. WHEATON, OF DES MOINES, IOWA.

TOOL.

1,408,961.

Specification of Letters Patent.

Patented Mar. 7, 1922.

Application filed August 4, 1920. Serial No. 401,149.

To all whom it may concern:

Be it known that I, SHELDON A. WILLIAMS, a citizen of the United States, and a resident of Des Moines, in the county of 5 Polk and State of Iowa, have invented a certain new and useful Tool, of which the following is a specification.

The object of my invention is to provide a tool of very simple and inexpensive construction, particularly adapted for use in 10 shaping fiber gears.

It is quite common in automobile construction to connect the timer shaft with the engine shaft by means of a fiber gear mounted 15 on the cam shaft. The fiber gear is mounted between two discs or plates, each provided with gear teeth, and the gear on the timer shaft, as well as the gear on the engine are of such width that they mesh 20 only with the fiber gear on the cam shaft.

In the use of the fiber gear, the teeth gradually become elongated and project beyond the teeth of the discs between which the fiber gear is enclosed. When the fiber 25 gear has become mis-shapened to a certain extent, it can not be longer used, and the common practice is to return it to the factory for exchange or credit or to re-shape it by an elaborate and expensive process 30 with a lathe.

With these and other objects in view, my invention consists in the construction and arrangement and combination of the various parts of my device, whereby the objects contemplated are attained, as hereinafter more 35 fully set forth, pointed out in my claims, and illustrated in the accompanying drawings, in which:

Figure 1 shows a side elevation of a portion 40 of a gear casing with parts of the gear casing shown in section, and parts broken away, with my improved tool installed thereon.

Figure 2 shows a detail, sectional view 45 taken on the line 2—2 of Figure 1; and

Figure 3 shows an enlarged, side elevation of the roller device.

In the accompanying drawings, I have used the reference numerals 10 and 11 for 50 indicating the lower and upper casing members at the front end of an engine.

Extended through the casing formed by the members 10 and 11 is an engine shaft 12, on which is a pinion 13. Connected with 55 the casing 11 and extending away there-

from is a casing 14. The casing 14 has therein, spaced from the casing 11, an opening 15, which is ordinarily covered by casing member.

The timer shaft extends into the opening 60 15 and ordinarily has on it a gear, not here shown.

Extending through the casings 11 and 14 is the cam shaft 16, on which is the fiber gear 17, on the opposite sides of which are 65 metal discs 18 and 19, having teeth on their periphery, which corresponds with the teeth of the fiber gear.

It is found in the use of the fiber gear interposed between the two metal gears, 70 that the teeth of the fiber gear become gradually forced outwardly and mis-shapened. The teeth then extend beyond the teeth of the discs 18 and 19, as illustrated for instance at capital A in Figure 3.

In order to reduce these fiber gear teeth to proper shape the ordinary practice, as has already been said, is to entirely remove the fiber gear, re-shape it, and then put it back in position. Frequently the fiber gear 80 can not be repaired at all.

For reducing the teeth of the fiber gear to their normal shape, I have provided a special tool, which includes a cross bar 20, through which are extended bolts 21. These 85 bolts are extended through holes in the casing 14, which ordinarily receive the bolts for the cover for the opening 15.

The bar 20 is formed with a bearing 22 for a shaft 23. Extending away from the 90 shaft 23 at right angles thereto is a handle 24. Extending away from the shaft 23 in the opposite direction from the handle 24 and parallel therewith is an arm 25 on the end of which is a spindle 26, arranged at 95 right angles to the arm 25, as shown, for instance, in Figure 2.

On the spindle 26 is a roller 27, which may be made of steel or other material, harder than the fiber gear.

The engine shaft is rotated in any suitable way in the use of my tool and it will be seen that the fiber gear will then be rotated from the pinion 13. The handle 24 is then grasped and the roller 27 is held against the teeth 100 of the fiber gear, as illustrated in Figure 3.

In Figure 3, I have shown at capital A, the fiber teeth projected beyond the teeth 105 18a of the disc 18, while at capital B, I have shown the fiber discs after my process 110

has been practiced with the use of the tool herein mentioned, and the fiber teeth have been reduced to their normal shape.

The roller 27 forces the teeth of the fiber gear inwardly and the meshing of the fiber gear with the teeth of the pinion 13 gives to the teeth of the fiber gear their proper shape.

It will be understood that the change in 10 the fiber teeth from their shape shown at A in Figure 3 to their shape shown at B is not accomplished at one revolution of the fiber gear, but I have made the showing in Figure 3 for the purpose of properly illustrating the condition of the fiber gear before and after, the practice of my process.

Where my tool is used, it is only necessary to remove the cover from the opening 15 and to remove the gear on the timer shaft 20 and install my tool. Then when the engine shaft is rotated, the roller 27 may be held against the teeth of the fiber gear, until such teeth are reduced to their normal shape and size.

It is obvious that it is unnecessary to remove the fiber gear from the engine and that the entire re-shaping of the teeth of the fiber gear may be very quickly and inex-

pensively accomplished, when my process is compared with the old way of accomplishing the same purpose.

It will be seen that some variations may be made in the construction of the tool without departing essentially from the real spirit and purpose of my invention.

I claim:

1. In a device of the class described, a supporting member having a bearing, a shaft mounted in said bearing, arms extending from said shaft in substantially opposite 40 directions, a spindle on one of said arms arranged at right angles to the arm, and a roller on said spindle.

2. In a device of the class described, the combination of a fiber gear having metal 45 discs at its sides, provided with teeth corresponding with the teeth of the fiber gear, a metal gear in mesh with the fiber gear, a supporting member having a bearing, a shaft mounted in said bearing, arms on said shaft, 50 and a spindle on one of said arms, having thereon a rotary device adapted to be pressed against the teeth of the fiber gear.

Des Moines, Iowa, July 26, 1920.

SHELDON A. WILLIAMS.
